UNITED STATES PATENT OFFICE

137,980

DESIGN FOR A CLOTHESPIN DISK TOY

Frank E. Hoffman, New York, N. Y.

Application March 10, 1944, Serial No. 112,842

Term of patent 7 years

(Cl. D34—15)

To all whom it may concern:

Be it known that I, Frank E. Hoffman, a citizen of the United States, residing at 52 Gramercy Park North, city, county, and State of New York, have invented a new, original, and ornamental Design for a Clothespin Disk Toy, of which the following is a specification, reference being had to the accompanying drawing, forming part thereof.

Fig. 1 is a side view of a clothespin disk toy, showing my new design; and

Fig. 2 is an edge view thereof.

I claim:

The ornamental design for a clothespin disk toy, as shown.

FRANK E. HOFFMAN.
